UNITED STATES PATENT OFFICE.

WILLIAM E. ESCHENBRENNER, OF NEW YORK, N. Y., ASSIGNOR OF ONE-HALF TO
HENRY W. ESCHENBRENNER, OF NEW YORK, N. Y.

CHAIR-BED.

1,343,044.

Specification of Letters Patent. Patented June 8, 1920.

Application filed November 20, 1919. Serial No. 339,483.

To all whom it may concern:

Be it known that I, WILLIAM E. ESCHENBRENNER, a citizen of the United States, and a resident of the city of New York, borough 5 of the Bronx, in the county of Bronx and State of New York, have invented a new and Improved Chair-Bed, of which the following is a full, clear, and exact description.

10 This invention relates to improvements in chair beds, and more particularly to a device which is capable of performing both functions, namely, a chair and a bed, an object of the invention being to provide an 15 improved construction and mounting for a plurality of sections which enable the sections to be supported in a horizontal line to form a bed, or assembled in an improved manner to form a seat and a back constituting a chair.

20 With these and other objects in view the invention consists in certain novel features of construction and combinations and arrangements of parts as will be more fully 25 hereinafter described and pointed out in the claims.

In the accompanying drawings—

Figure 1 is a view in longitudinal section through the center of the device when the 30 parts are assembled in the form of a chair;

Fig. 2 is a view in rear elevation;

Fig. 3 is a view in longitudinal section through the center of the device when the parts are positioned to form a bed;

35 Fig. 4 is a plan view of Fig. 3; and

Fig. 5 is a view in transverse section on the line 5—5 of Fig. 3.

40 My improved device comprises a main supporting section A having a cushion 1 thereon which coöperates with a back cushion 2 and an extension cushion 3 to form a bed, as will be hereinafter explained.

45 The main section A comprises a pair of side members 4, 4, which are connected by transverse bars 5 and 6 at the rear and front respectively. The extension cushion is made with inclined side members 7, 7, which are adapted to slide on inclined guides 8, 8, secured to the inner faces of the frames 4 and movable across the front transverse 50 bar 6.

The cushion extension 3 is provided with a relatively heavy transverse bar 9 and the

latter has a tongue 10 which engages the transverse bar 6 and limits the forward 55 movement of the extension. A pair of supporting legs 11 are hingedly connected to the extension, as shown at 12, and are provided with braces 13 which may constitute hooks engaging eyes 14 on the legs to support the legs when in vertical position, but permit the legs to be folded upwardly when the extension is moved inwardly and downwardly along the inclined guides 8. The legs, when in upright position, are held 60 against the front transverse bar 15 of the cushion extension 3 so that they are securely braced and a strong structure is had.

65 The seat cushion 1 is supported at its rear upon blocks 16 secured to the frames 4 and 70 at its forward end is supported on a shoulder 17 formed on the bar 9. The cushion 1 has a rearwardly projecting lip 18 which supports the forward end of the back cushion 2, the main portion of said back cushion 75 being supported on a rearwardly sliding frame 19 when the cushion is in horizontal position to form a bed. This frame 19 slides in grooves 20, 20, in the inner faces of the frames 4 and is provided with legs 21 at its 80 rear end, as clearly shown in Fig. 3. When the cushion extension 3 is located within the main section A, it will be in a lower plane than the cushion 1 by reason of the fact that said extension slides downwardly on the 85 guides 8 so that it fits under the cushion 1, as shown clearly in Fig. 1. The sliding frame 19 is mainly inclosed within the section A when the said sliding frame is moved forwardly and only the legs 21 and the rear 90 end of the frame 19 are exposed, as shown clearly in Fig. 2.

95 The side frames 4, 4, are provided with sockets 22 to receive pins 23 which extend downwardly from arm frames 24. In other words, the arm frames 24 of the chair are removably connected to the main section by means of the pins 23 and the sockets 22 and these arm frames extend rearwardly and are provided with notches 25 to receive 100 a cross rod 26 and hold the back cushion 2 at the desired angle when the device is in use as a chair.

105 In making these arm frames 24 removable, the device can be rendered more comfortable as a bed and make it easier to use

the proper bed clothes or covers which might be interfered with by the arm frames. The arm frames may, of course, be variously made but preferably comprise upper and lower bars 27 and 28 connected by uprights 29.

To prevent longitudinal movement of the seat section 1, the latter is preferably provided with lugs 31 which engage the blocks 16 and prevent rearward movement of the section 1, thus acting as a centering or positioning means for maintaining the seat section in proper position.

The operation is as follows: When the device is in use as a chair, the section 3 is located under the section 1 and the latter at its forward edge is supported thereon and at its rear edge is supported on the blocks 16. The back cushion 2 may, if desired, be hingedly connected to the seat cushion 1, as shown at 30, but this is purely optional and may be dispensed with if desired.

When the device is to be used as a bed, the arm frames 24 are preferably removed, and the section 3 drawn forwardly to the position shown in Fig. 3, the legs 11 being swung downwardly and locked in position by the hooks 13. The rear extension frame 19 is then drawn outwardly and supports the cushion 2 in alinement with the cushions 1 and 3, as shown clearly in Figs. 3 and 4, so that a comfortable bed is provided.

Various slight changes may be made in the general form and arrangement of parts described without departing from the invention, and hence I do not limit myself to the precise details set forth but consider myself at liberty to make such changes and altera-

tions as fairly fall within the spirit and scope of the appended claims.

40

I claim:

1. A combination chair and bed, comprising a main section, removable arm frames on said main section, a seat cushion on the main section, a back cushion, a rod across the arms supporting the back cushion when the device is in use as a chair, a rearwardly movable frame having sliding engagement with the main section and adapted to support the back cushion when the latter is in horizontal position, a forwardly movable extension normally under the seat cushion, inclined guides on the main section supporting the extension, a tongue on the extension engaging the main section and limiting its forward movement, legs hingedly connected to said extension, and braces adapted to hold the legs in vertical position when the extension is in its forward position and permit said legs to fold upwardly when the extension is moved to its rearward position.

2. A combination chair and bed, comprising a main section, a forwardly movable extension guided in its movement by the main section, a rearwardly movable frame guided in its movement by the main section, cushions on the extension, the main section and the frame located in alinement when the device is in use as a bed, said seat cushion supported at its forward edge on a shoulder of the extension and at its rear edge on the main section, and a rearwardly projecting lip on the seat cushion supporting the forward edge of the back cushion.

WILLIAM E. ESCHENBRENNER.
